CLAIM

The ornamental design for a container with lid as shown and described.

DESCRIPTION

FIG. 1 is a top perspective view of a first example of a container with lid with a handle in a first position.

FIG. 2 is a bottom perspective view of the container with lid of FIG. 1.

FIG. 3 is a front view of the container with lid of FIG. 1.

FIG. 4 is a back view of the container with lid of FIG. 1.

FIG. 5 is a right side view of the container with lid of FIG. 1.

FIG. 6 is a left side view of the container with lid of FIG. 1.

FIG. 7 is a top view of the container with lid of FIG. 1.

FIG. 8 is a bottom view of the container with lid of FIG. 1.

FIG. 9 is a top perspective view of the container with lid of FIG. 1 with the handle in a second position.

FIG. 10 is a bottom perspective view of the container with lid of FIG. 9.

FIG. 11 is a front view of the container with lid of FIG. 9.

FIG. 12 is a back view of the container with lid of FIG. 9.

FIG. 13 is a right side view of the container with lid of FIG. 9.

FIG. 14 is a left side view of the container with lid of FIG. 9.

FIG. 15 is a top view of the container with lid of FIG. 9; and, FIG. 16 is a bottom view of the container with lid of FIG. 9.

The broken lines depict portions of the container with lid that form no part of the claimed design.

1 Claim, 16 Drawing Sheets
